US00D518316S

(12) **United States Design Patent**
Gusdorf et al.

(10) **Patent No.:** **US D518,316 S**
(45) **Date of Patent:** **** Apr. 4, 2006**

(54) **MULTI-LEVEL SHELF**

(75) Inventors: **Michael L. Gusdorf**, St. Louis, MO (US); **Hsing-Ling Li**, Crawford, MO (US)

(73) Assignee: **Industrial Wire Projects Inc.**, Sullivan, MO (US)

(**) Term: **14 Years**

(21) Appl. No.: **29/224,062**

(22) Filed: **Feb. 24, 2005**

(51) **LOC (8) Cl.** **06-04**

(52) **U.S. Cl.** **D6/474; D6/464**

(58) **Field of Classification Search** D6/460, D6/461, 468, 464, 474, 477-479, 429; 108/11, 108/65, 137, 59, 91, 92, 96; 211/42, 85, 87.01, 211/90.01, 107, 111, 119.003, 134, 186, 153, 211/189, 195, 201, 175

See application file for complete search history.
